MANIFOLD ATTACHMENT FOR INTERNAL COMBUSTION ENGINES

Application filed May 14, 1930. Serial No. 452,285.

This invention relates to fuel systems for internal combustion motors, and constitutes a continuation in part of my copending application, Serial No. 422,331, filed January 5 21, 1930.

An object of the invention is the provision of a carburetor attachment for an internal combustion engine, adapted to automatically establish communication between the interior 10 of the intake manifold with the atmosphere when the supply of fuel to the motor is diminished or completely cut off, and until the motor ceases operating under forced 15 momentum, at a rate of speed higher than that at which it will continue to operate upon the diminished amount of fuel.

It should be here pointed out that in the conventional carburetor the butterfly valve 20 which is operable from the driver's compartment, to control the passage of fuel to the motor, is not adapted to seal the passage through which fuel reaches the motor from the carburetor. Instead, the butterfly valve is held slightly open, the purpose being to 25 permit a small amount of fuel to pass when the valve is in its most nearly completely closed position, so that the motor can idle. This produces an undesirable condition when the carburetor is used upon a variable 30 speed motor, because when the supply of fuel to the motor is suddenly diminished or completely cut off, the motor is still turning over at a relatively high rate under forced momentum, due to the velocity of its 35 crankshaft and flywheel, and the momentum of the vehicle of which the motor is a part, provided the motor is not disconnected therefrom. In this manner, a relatively high 40 vacuum is created in the intake manifold due to the pumping action of the pistons and valves operating under forced momentum, thus drawing a much larger quantity of liquid fuel through the carburetor than the carburetor is capable of atomizing in view of 45 the fact that the passage of such atomized fuel past the butterfly valve is restricted. Accordingly, as the motor is slowed down, each of its cylinders is drawing a very highly enriched fuel mixture thereinto. In fact, 50 so rich is this fuel mixture, that it is not

explosive, and is discharged through the exhaust manifold as unburned fuel. This not only results in increased cost of the operation of the motor, but it also produces that condition known as "gassing" wherein a cloud of obnoxious gas is discharged from the exhaust. This condition is particularly noticeable in the case of relatively large trucks and motor busses. When the operator of 55 such a vehicle, is shifting gears, the motor will be running at a relatively high speed with the low-ratio gears enmeshed, and then the load on the motor suddenly relieved and the supply of fuel thereto, shut off while the gears of a higher ratio are engaged. This sudden discontinuance of the supply of fuel to the motor, will result in the discharge of a 60 cloud of foul-smelling and poisonous gas behind the vehicle, a condition which is particularly undesirable in districts of heavily 65 congested traffic, because of the relatively high percent of the carbon monoxide gases which are thus expelled to the atmosphere. It is an object therefore, of the present invention, to provide a device for relieving this 70 undesirable condition.

A more detailed object is the provision of a carburetor attachment capable of operating as above indicated, which is normally held 75 inoperative by spring action, but in which this spring action is suddenly relieved to permit operation of the attachment when the pressure within the intake manifold has been reduced below a predetermined value.

Another object is to provide means for 80 bringing the opening movement of the valve which constitutes one of the operative parts of the invention, to a gradual stop at the end of its opening movement, thus eliminating the noise and wear which would be coincident 85 with suddenly stopping its motion.

A still further object is to provide a device 90 of this general character, which is composed of a relatively few parts, each of which is of simple construction; with the result that the device is capable of being manufactured, installed and operated with the greatest economy and efficiency.

The invention possesses other objects and 95 advantageous features, some of which, with 100

those enumerated, will be set forth in the following description of the invention's particular embodiment which is illustrated in the drawing accompanying and forming a part of the specification.

Referring to the drawing:

Figure 1 is a side elevation of an internal combustion engine showing the carburetor attachment of the present invention, operatively installed thereupon.

Fig. 2 is a longitudinal, medial, vertical sectional view of the carburetor attachment in normal or closed position.

Fig. 3 is a view similar to Fig. 2, but showing the movable portions of the device in the positions assumed thereby when the pressure within the intake manifold has decreased sufficiently to cause actuation of the device.

Fig. 4 is a transverse, vertical sectional view taken upon the line 4-4 of Fig. 3, with the direction of view as indicated.

The device of the present invention is shown operatively installed for use in conjunction with an internal combustion engine 6 of conventional design, and comprising a cylinder block 7, intake and exhaust manifolds 8 and 9 respectively, a carburetor 11 of conventional design, coupled to the intake manifold 8, and an exhaust pipe 12 communicating with the exhaust manifold 9.

My improved carburetor attachment which is indicated in its entirety at 13, is interposed between the intake manifold 8 and the carburetor 11, so that in effect, it is actually interposed into the intake manifold 8, inasmuch as the vaporized fuel from the carburetor 11, passes through the attachment 13 and thence through the intake manifold 8 on its way into the combustion chambers of the cylinder block 7.

The attachment 13 consists of a tubular housing 16 having flanges 17 and 18 at its upper and lower ends respectively, whereby it may be firmly attached to the flanges 19 and 21 of the intake manifold 8 and the carburetor 11 respectively. In general configuration, the housing 16 resembles a conventional T pipe fitting, inasmuch as it has a side inlet 22 interiorly threaded as indicated at 23, for the reception of a valve cage 24 having a spider 26 extending from its outer end to firmly support a valve guide 27 within which the stem 28 of a mushroom type valve 29 is reciprocable. A valve seat 31 formed on the inner face of the valve cage 24, encircles a port 32 through which communication between the interior of the housing 16 and the atmosphere, may be established when the valve 29 moves off the seat 31; and inasmuch as the valve seat 31 is disposed on the inner face of the valve cage 24, opening motion of the valve 29 must be inwards with respect to the housing 16.

The valve seat 31 is formed in a counter-bored portion 33 in the inside face of the

valve cage 24, and a peripheral flange 34 is provided upon the valve 29. The inside diameter of the counterbore 33 is only slightly greater than the outside diameter of a peripheral flange 34 formed on the valve 29. This flange lies inside the counterbore 33 when the valve 29 engages the seat 31, thus producing a very rapid flow of air through the restricted annular space between the flange 34 and the counterbore 33 at the instant that the valve opens; and the velocity of the air in so moving, causes the positive and rapid movement of the valve 29 to fully open position. Within the end 36 of the counterbore 33 which is proximal to the body of the housing 16, a preferably removable ring 37 is disposed, this ring however, being firmly secured in position so that it will not be jarred loose during normal use of the device. The inside diameter of the ring 37 is preferably slightly greater than that of the inner end of the counterbore 33, but still only slightly greater than the outside diameter of the flange 34 of the valve 29, so that when the valve starts to close, it encounters a stream of air flowing at relatively great velocity through the restricted annular space between the flange and the ring 37. This holds the valve open until the differentiation of pressure within and without the intake manifold 8 has been sufficiently nearly equalized to reduce this flow to a relatively low velocity, whereupon the valve 29 can move closed against the relatively slow flow of air. Moreover, the ring 37 is interchangeable, to permit fine adjustment of the device to accommodate the circumstances of any particular installation.

Upon a reduced hub 41 of the valve guide 27, external threads 42 are formed for the reception of a nut 43 adapted to clamp the top 44 of a housing 46 against a flange 47 of the valve guide 27, so as to rigidly but removably mount the housing 46 in position. The parts are so proportioned that when the housing 46 is so secured, its bottom edge 48 is pressed tightly against a seat 49 which is formed on the valve cage 24, so that the only entrance into the housing 46 is by way of a side inlet 51, the bore 52 of which communicates with the interior of the housing 46. The inlet 51 is provided with a flange 53, whereby a conduit 54 may be attached thereto, this conduit 54 leading to a sleeve 56 encircling but slightly spaced from a portion of the exhaust manifold 9, thus insuring that all the air entering the housing 46 will first have its temperature raised by being forced to pass in close proximity to a heated exhaust manifold 9.

A pair of lugs 61 are provided upon the outer face of the top 44 of the housing 46, these lugs being disposed diametrically opposite each other with respect to the axis of the valve stem 28 which passes completely through the valve guide 27, and hence to the

exterior of the housing 46. Upon each of the lugs 61, an arm 62 is pivoted as by a pivot pin 63, and each arm 62 carries a roller 64. A head 66 is threaded upon the outer end of the 5 valve stem 28, a lock nut 67 being employed to clamp the head 66 in adjusted position upon the threads 68 on the valve stem 28, whereby the head is secured thereto. The head 66 is substantially conical in configuration, thus providing inclined surfaces 69 10 against which the rollers 64 are pressed by means of contractile springs 71 which are under tension between pins 72 extending laterally from the arms 62; with the result that 15 the arms 62 are continually urged toward each other.

However, the sloping surface 69 of the head 66, is provided with a raised portion or shoulder 73 intermediate the limits thereof, this 20 shoulder being so positioned that the rollers 64 are in engagement therewith as indicated upon Fig. 2 when the valve 29 is seated, i. e., in that position in which the port 32 is tightly closed. As clearly shown upon Figs. 2 and 3 25 however, the approaches 74 and 76, to the shoulder 73, are rounded so that movement of the rollers 64 over the shoulder 73, is facilitated.

The outer approach 76 to the shoulder 73, 30 gradually curves outwards about a radius slightly greater than the radius of the rollers 64; with the result that the extreme outer end of the head 66, flares with gradually decreasing pitch, until it merges into a peripheral portion 77 which extends substantially perpendicularly with respect to the axis of the valve stem 28. This perpendicularly extending flange serves as means for limiting the inward movement of the flange 29, inasmuch as when it impinges against the rollers 64, the force exerted thereby against the rollers in moving inwards, will tend to press the rollers in lines parallel to the axis of the valve stem 28, in contradistinction to the direction in which the rollers are pressed when they are engaged by any of the flaring portions of the head 66. When these flaring portions engage the rollers 64, and the stem 28 is moving inwards, a wedging action is 40 developed against rollers 64, causing arms 62 to swing outwards against the force exerted by the springs 71. Hence, these springs 71 continually resist inward movement of the valve 29. However, in view of the fact that 45 the innermost approach 74 to the shoulder 63, is of less pitch than the approach 76, the resistance offered by the arms 62 and rollers 64 to inward movement of the valve 29, is considerably greater when the rollers 64 engage 50 the approach 74, than it is after the rollers 64 have passed the shoulder 73 and are in engagement with the more steeply inclined approach 76. Moreover, the tension of the springs 71 may be regulated, inasmuch as 55 each is connected to one of the pins 72 by

means of an eye 78 encircling that pin, and a nut 79 threaded onto the shank 80 of the eye.

A second nut 81 is threaded upon the hub 41; and a coil spring 82 is under compression between this nut 81 and the inner end 83 of 70 the head 66, so that this spring 82 is continually urging the head 29 into port-closing position.

Operation

75

When the motor 6 is operating under normal conditions, i. e., when fuel is being supplied thereto at a given rate to maintain operation of the motor 6 at a given speed, the valve 29 will remain seated, owing to the 80 fact that the spring 82 is of such strength and the adjusting nut 81 has been so positioned that the force of the spring 82 is just sufficient to maintain the valve 29 seated against the pressure of the air against the 85 under surface of the valve 29. In other words, the spring 82 is of sufficient strength to overcome the differentiation in pressure between the inner and outer faces of the valve 29 which obtains as a result of the 90 partial vacuum existing within the intake manifold 8 during normal operation of the motor.

However, when the butterfly valve of the carburetor 11 is suddenly closed so as to decrease or substantially completely shut off the supply of fuel to the motor, the pressure within the intake manifold 8 and consequently that within the tubular portion of the housing 16, will be very greatly diminished; with 100 the result that the valve 29 will be drawn inwards away from the seat 31 and against the action of the coil spring 82. This inward motion of the valve 29 will also be against the action of the springs 71, inasmuch as 105 the inward motion of the head 66 wedges the rollers 64 and the arms 62 apart, thus stretching the springs 71 which are under tension between the arms 62. The shoulder 73 which is formed on the inclined surface of the head 110 66, cooperates with the spring 82 in holding the valve 29 seated until the pressure within the intake manifold has decreased below a predetermined value, because its presence in engagement with the rollers 64 when the valve 115 is fully seated, necessitates the exertion of a greater force against the valve 29, to cause motion thereof, as compared to the force required to cause similar motion when the rollers 64 are in engagement with a more steeply inclined portion 76 of the head 66. Hence, 120 the shoulder 73 serves to resist initial opening movement of the valve, and to permit the valve to move away from the seat 31 more freely, subsequent to initial movement thereof. This detail of construction also serves to prevent the valve 29 from moving away from port-closing position until the pressure within the intake manifold, has decreased 125 below a predetermined value. It also causes 130

the valve to move to fully open position relatively suddenly, because of the fact that instantly the rollers 64 have passed the shoulder 73, the amount of energy required for further motion of the valve, will be materially decreased; with the result that the valve will snap to fully open position.

The restricting ring 37 also works toward this same end, inasmuch as when the valve 10 initially opens, a relatively restricted passageway is provided between the peripheral flange 34 of the valve and the inside circumference of the ring 37; and when the valve has moved further away from the seat 15 31, this passageway is materially increased, thus permitting freer passage of air therepast.

The fact that the outer end 77 of the head 66 flares with gradually increasing pitch, 20 causes the opening motion of the valve 29 to be brought to a gradual stop. The rollers 64, in rolling from the approach 76 toward the outer end of the head 66, will impinge against the perpendicular portion 77 of the 25 head, more gradually than would be the case if this portion of the head flared more abruptly, i. e., if the curvature of this portion of the head were about a radius equal to or smaller than that of the rollers 64. However, 30 the principal function of the restricting ring 37, is to more accurately determine the extent to which the pressure within the intake manifold must be increased before the valve closes, and then permit the spring 82 to snap 35 the valve 29 closed with relative rapidity. In other words, at just the instant that the pressure within the intake manifold raises to only slightly less than that which obtains under normal working conditions, the valve 40 will snap closed, so that the normal supply of fuel is again fed to the motor.

The threaded connection of the head 66 upon the valve stem 28, permits nice adjustment of the device, so that the rollers 64 45 seat against the inner approach 74 to the shoulder 73 when the valve 29 is in engagement with the valve seat 31. Adjustment of the nut 81 causes variation of the pressure exerted by the spring 82 against the head 66, whereby the extent of raising of the pressure within the intake manifold 8, necessary to cause the valve 29 to be moved to its seat, may accurately be predetermined. Also, 50 the force exerted by the rollers 64 against the conical head 66 so as to resist inward motion thereof, may be varied by manipulation of the nuts 79 upon the shanks 80 of their respective eyes 78, as will readily be understood.

60 It is to be understood that the details of the invention as herein disclosed, are subject to alteration within the spirit or scope of the appended claims.

I claim:

65 1. In combination with means for intro-

ducing fuel to the intake manifold of an internal combustion engine, a housing adapted to be interposed into said manifold and having a port in the wall thereof, a valve associated with said port and adapted to open 70 the port by moving therefrom inwards with respect to the housing, spring means resisting inward movement of said valve, and means cooperative with said spring means for reducing the resistance offered thereby subsequent to initial inward movement of said valve.

2. In combination with means for introducing fuel to the intake manifold of an internal combustion engine, a housing adapted 80 to be interposed into said manifold and having a port in the wall thereof, a valve associated with said port and adapted to open the port by being moved therefrom inwards with respect to the housing when pressure 85 within the manifold is reduced below a predetermined value, spring means resisting inward movement of said valve, and means cooperative with said spring means for reducing the resistance offered thereby subsequent 90 to initial inward movement of the valve.

3. In combination with means for introducing fuel to the intake manifold of an internal combustion engine, a housing adapted 95 to be interposed into said manifold and having a port in the wall thereof, a valve associated with said port and adapted to open the port by being moved therefrom inwards with respect to the housing when pressure within the manifold is reduced below a predetermined value, spring means resisting inward movement of said valve, means cooperative with said spring means for reducing the resistance offered thereby subsequent to initial inward movement of the valve, and means 100 for reducing the effect on said valve of pressure differentiation against opposite faces thereof subsequent to initial movement of the valve.

4. In combination with means for introducing fuel to the intake manifold of an internal combustion engine, a housing adapted to be interposed into said manifold and having a port in the wall thereof, a valve associated with said port and adapted to open 110 the port by being moved therefrom inwards with respect to the housing when pressure within the manifold is reduced below a predetermined value, spring means resisting inward movement of said valve, means cooperative with said spring means for reducing the resistance offered thereby subsequent to initial inward movement of the valve, and means for suddenly reducing the effect on said valve 115 of pressure differentiation against opposite faces thereof subsequent to initial movement of the valve.

5. In combination with means for introducing fuel into the intake manifold of an internal combustion engine, a housing adapted 120

to be interposed into said manifold and having a port in a wall thereof, a valve arranged inside said port and adapted to close the port by moving outwards with respect to said housing, a stem rigid with said valve, a head carried by said stem, an arm pivoted to said housing, a roller carried by said arm, and spring means urging said roller against the head to move the valve into port-closing position.

6. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem and having an inclined surface, an arm pivoted to said housing, a roller carried by said arm, and spring means urging said roller against said inclined surface of the head to move the valve into port-closing position.

7. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem and having an inclined surface, a shoulder on said inclined surface intermediate the limits thereof, an arm pivoted to said housing, a roller carried by said arm, and spring means urging said roller against said inclined surface of the head to move the valve into port-closing position.

8. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, arms pivoted to said housing on opposite sides of said stem, a roller carried by each of said arms, and spring means under tension between said arms, urging said rollers against the head to urge said valve into port-closing position.

9. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, arms pivoted to said housing on opposite sides of said stem, a roller carried by each of said arms, spring

means under tension between said arms, urging said rollers against the head to urge said valve into port-closing position, and means operative subsequent to initial opening movement of said valve for decreasing the resistance offered by said spring means to further opening movement thereof.

10. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, arms pivoted to said housing on opposite sides of said stem, a roller carried by each of said arms, and spring means under tension between said arms, urging said rollers against the head to urge said valve into port-closing position, and a shoulder on said head engageable by said rollers when the valve is in port-closing position whereby said spring means offers greater resistance to initial opening movement of the valve.

11. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, arms pivoted to said housing on opposite sides of said stem, a roller carried by each of said arms, spring means under tension between said arms, urging said rollers against the head to urge said valve into port-closing position, and a shoulder on said head engageable by said rollers when the valve is in port-closing position whereby said spring means offers greater resistance to initial opening movement of the valve, the approaches to said shoulder being rounded to facilitate movement of said rollers therest.

12. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, arms pivoted to said housing on opposite sides of said stem, a roller carried by each of said arms, spring means under tension between said arms, urging said rollers against the head to urge said valve into port-closing position, a shoulder on said head engageable by said rollers when the valve is in port-closing position whereby said spring means offers greater resistance to initial opening movement of the valve, and

means for bringing the opening movement of said valve to a gradual stop.

13. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, arms pivoted to said housing on opposite sides of said stem, a roller carried by each of said arms, spring means under tension between said arms urging said rollers against the head to urge said valve into port-closing position, and a shoulder on said head engageable by said rollers when the valve is in port-closing position whereby said spring means offers greater resistance to initial opening movement of the valve, the periphery of said head being gradually flared outwards to perpendicularity with the axis of said stem and about a radius slightly greater than that of said rollers
14. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, an arm pivoted to said housing, a roller carried by said arm, and spring means urging said roller against the head to move the valve into port-closing position,
15. In combination with means for introducing fuel into the intake manifold of an internal combustion engine, a housing adapted to be interposed into said manifold and having a port in a wall thereof, a valve arranged inside said port and adapted to close the port by moving outwards with respect to said housing, a stem rigid with said valve, a head carried by said stem, an arm pivoted to said housing, a roller carried by said arm, spring means urging said roller against the head to move the valve into port-closing position, a spring interposed between said stem and said housing resisting opening movement of the valve, and means for varying the force exerted by said spring against the stem.
16. In a device for admitting air to the intake manifold of an internal combustion engine, a housing communicating with said manifold and having a port in a wall thereof, there being a passage leading from said port to the interior of said housing, a valve reciprocable within said passage and adapted to close said port by moving outwards with

respect to said housing, said valve being of only slightly smaller area than the cross sectional area of said passage, resilient means resisting inward movement of said valve, and means cooperative with said resilient means for reducing the resistance offered thereby subsequent to initial inward movement of said valve.

17. In a device for admitting air to the intake manifold of an internal combustion engine, a housing communicating with said manifold and having a port in a wall thereof, there being a passage leading from said port to the interior of said housing, a valve reciprocable within said passage and adapted to open said port by being moved therefrom inwards with respect to the housing when pressure within the manifold is reduced below a predetermined value, resilient means resisting inward movement of said valve, and means cooperative with said resilient means for reducing the resistance offered thereby subsequent to initial inward movement of said valve.

18. In combination with means for introducing fuel into the intake manifold of an internal combustion engine, a housing adapted to be interposed into said manifold and having a port in a wall thereof, a valve adapted to close the port by moving outwards with respect to said housing, a stem rigid with said valve, a head carried by said stem, an arm pivoted to said housing, a roller carried by said arm, and spring means urging said roller against the head to move the valve into port-closing position.

19. In combination with means for introducing fuel into the intake manifold of an internal combustion engine, a housing adapted to be interposed into said manifold and having a port in a wall thereof, a valve adapted to close the port by moving outwards with respect to said housing, a stem rigid with said valve, a head carried by said stem and having an inclined surface, an arm pivoted to said housing, a roller carried by said arm, and spring means urging said roller against said inclined surface of the head to move the valve into port-closing position.

20. In combination with means for introducing fuel into the intake manifold of an internal combustion engine, a housing adapted to be interposed into said manifold and having a port in a wall thereof, a valve adapted to close the port by moving outwards with respect to said housing, a stem rigid with said valve, a head carried by said stem, an arm pivoted to said housing, a roller carried by said arm, and spring means urging said roller against the head to move the valve into port-closing position.

21. In combination with means for introducing fuel into the intake manifold of an internal combustion engine, a housing adapted to be interposed into said manifold and

having a port in a wall thereof, a valve adapted to close the port by moving outwards with respect to said housing, a stem rigid with said valve, a head carried by said stem, 6 an arm pivoted to said housing, a roller carried by said arm, spring means urging said roller against the head to move the valve into port-closing position, a spring interposed between said stem and said housing 10 resisting opening movement of the valve, and means for varying the force exerted by said spring against the stem.

In testimony whereof I have signed my name to this specification.
